ELECTRIC SWITCH

Arthur C. Gaynor, Stratford, Conn., assignor to
 Pass & Seymour, Inc., a corporation of New
 York

Application May 15, 1930, Serial No. 452,545
 Renewed January 27, 1934

13 Claims. (Cl. 200—168)

This invention relates to electric switches, and more particularly, to improvements relating to the contact members thereof.

In my Patent No. 1,739,835, granted December 17, 1929, I have disclosed an arrangement whereby the contact members are not structurally attached to the base but are confined in operative position by being interposed between the base and a covering member of insulation. The advantages and savings of this structure have been retained in accordance with this invention and yet substantial improvements have been made.

One of the salient features of this invention is the provision of contact members which are interchangeable without the use of tools after a cover or cap is removed from the base of the switch, thereby permitting the base, cap and switch mechanism to be standard, i. e. the same, for a whole series of switches for performing different switching work, while only the contact members are special or unique to the different types of switches in the series. This is of great advantage in the manufacture of switches, for it permits mass production of the standard parts at reduced cost per unit, and to the user by permitting the conversion of a switch from one type to another merely by substituting different contact members for those previously used in the switch. For instance, it enables the conversion of the switch from any other one of the following types to a single pole switch, a single pole heavy duty switch, a single pole two-way switch, a two pole switch, a two pole two circuit switch, or a two pole three-way switch, merely by removing the contact members and substituting others therefor.

Another feature of this invention is the provision of the contact members in united pairs tied together by insulation or current-conducting strips (according to whether current is not or is intended to flow between the contact members) and adapted to be inserted in and removed from the base as a unit at one end of the switch, thereby facilitating the manufacture assembly and converting of the switch by avoiding the separate handling of each contact member.

A further feature is the provision of a non-circular plug on each connected pair of contact members, preferably one for each contact member, adapted to removably fit a companion socket in the base to support the contacts against substantial turning movements when mounted therein, the noncircular plugs preferably being tapped to hold a binding screw for securing a wire to the contact member.

And a further feature is the provision of means supported in an outlet box in the usual manner.

on the jaws of the contact members and on the casing and cap for preventing appreciable lateral movement of the jaws in their operative positions.

Other features and advantages will hereinafter appear.

In the accompanying drawings which illustrate one form of the invention, that at present preferred—

Fig. 1 is a plan view of the switch with the cover or cap removed.

Fig. 2 is a longitudinal sectional view taken on the line 2—2 Fig. 1.

Fig. 3 is a transverse sectional view taken on the line 3—3 Fig. 2.

Fig. 4 is a plan view of a corner of the base showing the non-circular socket for removably receiving the non-circular plug of the contact member.

Fig. 5 is a longitudinal section taken through the switch on the line 5—5 Fig. 1.

Fig. 6 is a perspective view of a pair of connected contact members made in accordance with this invention.

Fig. 7 is a schematic view showing the arrangement of the contact members when the switch is converted to a two pole three-way switch.

Fig. 8 is a schematic view showing the switch arranged to control two separate circuits, one circuit being closed while the other circuit is opened.

Fig. 9 is a similar view showing the switch arranged for two-pole operation.

Fig. 10 is a similar view showing the switch arranged for single-pole light-duty use.

Fig. 11 is a similar view showing the switch arranged for single-pole heavy-duty use.

Fig. 12 is a similar view showing the switch arranged to connect one pole of a circuit to two separate circuits alternately.

Fig. 13 is a perspective view of the united contact members used on the left and right hand ends of Fig. 8 and the right hand end of Fig. 12.

Figs. 14, 15, 16 and 17 are perspective views of the various contact plates employed to make the contact members used in the switches schematically indicated in Figs. 8 to 12.

As shown in the accompanying drawings, the present invention is embodied in a wall or outlet box supported switch and comprises a base 10 and a cap or cover 11 provided with aligned holes through which screws 12 extend upwardly and are threaded into nuts at the outside of the cap, or, as shown, into a threaded hole in a bridge-piece 13 by means of which the switch may be supported in an outlet box in the usual manner.

Instead of the switch mechanism being located almost entirely in the cavity in the base, as in my Patent No. 1,739,835, it is located in matched cavities provided in both the cap 11 and the base 10, as in my copending applications Serial No. 276,-
5 886, filed May 11, 1928; Serial No. 298,218, filed August 8, 1928; and Serial No. 309,978, filed October 3, 1928, in which the features of novelty not claimed herein are adequately disclosed and
10 claimed.

The switch mechanism proper comprises a polyhedral frame 14 removably supported in cavities in the base and cap and held in operative position against shifting movements by pillars 15 formed on the base and downwardly extending lugs 16 on the cap forming continuations of the pillars 15. Supported in the frame on a suitable axle is a handle 17 connected to a switch actuator 18 which engages an operating spring 19. The lower end of the spring is supported in a crank 20 having shaft portions 21 projecting through openings in the frame 14 and resting on bearings 22 on the frame. The extensions of the shaft portions 21 of the crank at each side thereof are made noncircular and support switch blades 23 and 23' which may be alike.

As disclosed in my copending application, Serial No. 298,218, filed August 8, 1928, either or both of these switch blades 23—23' may be insulated from the crank by an insulating block 24 which slidably fits the crank shaft extensions and permits the blade to have free lateral and floating movement thereon and also permits the blade to be slid on and off the shaft without the use of tools when the cap 11 and the frame 14 have been removed from the base, thereby permitting a switch blade to be removed from or applied to the crank at either side, as desired.

The arrangement is such that when the handle 17 is operated, the spring 19 is compressed and carried beyond the point of oscillation of the crank. When this is done, the spring expands and causes the crank 20 with the switch blades 23—23' carried thereby to rapidly oscillate with a snap action from one position of rest to another, the crank fulcruming on the bearings 22.

The switch blades 23—23' operate in chambers 25 at each side of the switch mechanism. Each chamber is formed by one side wall 26 of the base 10 and cap 11 and by the adjacent pillars 15 on the base and lugs 16 on the cap. The walls of each chamber 25 are relatively close together to restrict as much as possible the space in which the circuit is made and broken, so that the movement of the switch blades will fan out any arc which may tend to form in breaking a circuit. This is done for the further reason that the switch blades may be restricted in their lateral movements by these walls, this operation being facilitated by providing flares 27 on the ends of the switch blades.

The switch blades have, as stated, two positions of rest, and in either position the ends of the blades may or may not be engaged with co-operating contacts, according to the manner in which the switch is to be used. In the form of switch illustrated in Figs. 1, 2 and 3, the contacts are so arranged that in one position of rest one circuit is closed while the other is open, and in the other position of rest the first-mentioned circuit is open while the other is closed.

Accordingly, at one side of the switch, there is a contact A arranged near the bottom of the base and opposite it there is a contact B arranged near the top of the cap, while at the other side 75 of the switch and adjacent the lower contact A

is an upper contact marked B' and opposite it is a lower contact marked A' (see the schematic illustration, Fig. 8). Hence, when the switch blade is in the position shown in Fig. 2, the switch blade 23 is disengaged from the contacts A and B, thereby opening the circuit through wires 28 and 29 (Fig. 8), while the switch blade 23' engages its contacts B' and A' and closes the circuit including the wires 30 and 31. When the handle is operated, the switch blades are moved approximately 45° to cause the blade 23 to close the circuit between the contacts A and B while the blade 23' opens the circuit between the contacts B' and A'.

As stated above, the contacts, according to the present invention, are not fixedly secured to the base or cap but are removably mounted on the base and are held in operative position by the cap for purposes hereinafter more fully described. To accomplish this, the lower contacts A—A', 20 which it will be understood are alike, each has a flat surface 32 resting on the floor 33 of the switch blade chambers 25, and a vertical arm 34 and a horizontal portion 35, while the upper contacts B—B' each has a lug 36 resting on the inside surface 37 of the cap and a downwardly extending arm 38 terminating in a horizontal portion 39.

The arms are so arranged when mounted in the switch that the horizontal portions 35 and 39 lie in substantially the same horizontal plane and substantially in the plane of the line of division between the cap 11 and the base 10. The horizontal portions extend outwardly beyond the casing as illustrated in Fig. 2, and their ends may 35 preferably, but not essentially, lie in depressions 40 in the portions or ears 41 of the base which extend beyond the cap 11. Thus, when the cap 11 is secured to the base by the screws 12, the lower edge of the cap will engage the horizontal 40 portions 35 and 39 (or means carried thereby as will appear below) to prevent the contacts from moving bodily in a vertical plane, the lower edge of the cap engaging each contact member at the horizontal portion between the portion located 45 in the recess 40 and the vertical portions 34 or 38, holding the contacts down on the base or up against the surface 37 of the cap as the case may be.

Each contact member is preferably held 50 against movement in a horizontal plane by a noncircular plug 42 connected to the horizontal portions 35 and 39 thereof and each plug is adapted to removably fit a noncircular cavity 43 in the ear 41 extending down from the depression or recess 40. This plug 42 is provided with a screw-threaded aperture for the reception of a binding screw 44 below the head of which the wire of the circuit to be controlled by the switch may be secured.

The contacts are further prevented from shifting out of proper normal position by pairs of lugs 45 on the floor 33 and lug 46 on the roof 37 of the cap, the lugs 45—46 of each pair being so spaced that the bottom edges 32 of the contacts A—A' and the lugs 36 of the contacts B—B' respectively snugly fit between them, and thus accurately determine the positions of the switch blade engaging portions 47 and prevent lateral shifting movement thereof. This is an extremely 70 important feature of the present invention, for it permits the arms 34 and 38 of the contact members to have considerable length without danger of the jaws shifting from their proper positions and positively holds the switch blade engaging 75

portions in their proper positions to be engaged by the floating switch blades, besides permit the contact members to be removable from the base and cap without the use of tools.

5 The contacts A—A' or B—B' may be, as illustrated in Figs. 14 and 15, each structurally separate and independent of each other. But, to facilitate the operation of interchanging the contacts to make a switch of any particular type or convert a switch from one type to another, it is preferable that the contacts at each end of the switch be secured together in pairs and this structure is illustrated in Figs. 1, 2, 5 and 6.

In the case of the switch illustrated in Figs. 15 1, 2 and 8, where it is desired to separately control two circuits, the pairs of contacts A—B' and B—A' at each end of the switch are each connected by tie plates 48 of insulating material, see Fig. 13. Each tie plate 48 has a concave edge 49 20 to pass inside of the adjacent screw 12 and on its opposite edge it has a surface 50 adapted to engage one face of an abutment 51 between the pillars 17 and, in addition, notches 52 into which the upwardly extending arms 38 of the contacts 25 B—B' may extend.

In the case of the connected pair of contact members A—B' shown in Fig. 6, which is utilized in the form of switch diametrically indicated in Fig. 12, and in any case where the contact at one 30 end of the switch is intended to be electrically connected to the contact at the other end of the switch, as in the case of the contacts C—B' and D—A' respectively, in the form of switch shown in Fig. 11, a metallic tie plate 53 is employed instead 35 of the insulating tie plate 48, so that current will flow from the contact B' to contact A, (Figs. 6 and 12), or from the contact B' to the contact C, (Fig. 11) through the metallic tie plate 53, or from the contact A' to the contact D, (Fig. 11).

40 For uniformity of structure and to insure a complete interchangeability, even those contacts which are used alone at one end of the switch, as, for instance, the contacts A' and B' shown in Fig. 10, these contacts are provided with a dummy plate 54 as indicated in Fig. 10. These plates may or may not be of insulating material, as desired.

In making the paired contact members, the plates 48, 53 and 54 may be secured to the non-circular plug or plugs 42 in any suitable way. 50 It is preferable, however, that, as shown in Fig. 2, the ends of the plates which are to be fastened to the blocks 42, be provided with apertures through which a tubular portion of the plug extends so that the plates and the horizontal portions 55 35 and 39 of the contacts may be superposed and be fastened together by peening or spinning over a flange at the upper end of the block 42.

When it is desired to have both an upper and a lower contact at each corner of the switch, the practice diagrammatically illustrated in Fig. 7 may be followed. In this case, a contact C may be superposed with a contact A at one corner of the switch while contacts B' and D' may be superposed at the adjacent corner at the same end of the switch. Then, if the switch is to be a double pole three-way switch, contact members E and F may be mounted at the other corners of the switch, the contact member E having an upper contact B at one side and a lower contact A' at the other side connected by a bus bar 55 and a contact F having an upper contact C' at one side and a lower contact D at the other side connected by a bus bar 56.

75 Each of these pairs of contact members are

completely interchangeable with any other pair, and hence with the contact arrangement of the present invention, a switch may be converted from that shown in Figs. 1 and 2, or any other, to a single-pole light-duty switch (Fig. 10); a single-pole heavy-duty switch (Fig. 11); a single-pole two-way switch (Fig. 12); a two-pole switch (Fig. 9); a two-pole two-circuit switch (Fig. 8); or a two-pole three-way switch (Fig. 7), merely by removing the contact members and substituting 10 the proper contact members for the kind of switch desired.

This is extremely important from a manufacturing viewpoint, for it permits bases, caps and switch mechanism of all of the different types 15 of switches to be identical and requires only the special manufacture or assembly of the different kinds of contact members for the different purposes. Even this latter is facilitated by the present invention, for, with the exception of the contacts E and F in the form shown in Fig. 7, all of the other arrangements may be made with merely four different kinds of contacts, i. e. contacts A for the lower rear left and lower front 20 right positions, contacts B for the upper rear right and upper front left, contacts C for the upper rear left and upper front right, and contacts D for the lower rear right and lower front 25 left, all as viewed in Figs. 10 to 14 inclusive.

Variations and modifications may be made 30 within the scope of this invention and portions of the improvements may be used without others.

Having thus described the invention, what is 35 claimed as new and for which it is desired to obtain Letters-Patent, is:—

1. A snap switch comprising a base of insulation including terminal seats and sockets at corners of one face thereof, a cap for said base shaped to fit on said face and expose said seats, a switch blade, contact members adapted to be engaged and disengaged by said blade, said contact members each having a terminal portion extending to the exterior of the cap enclosed portion of the switch at the line of division between the cap and the base and provided with 45 an attached plug removably fitting in one of said sockets and threaded longitudinally to receive a binding screw, the exposed part of each terminal portion resting in one of said seats and being supported by said base, said contact members being held in the base solely by the cap. 50

2. A snap switch comprising a casing having a base and a cap; switch mechanism interposed between and enclosed by the base and cap and including a switch blade; and contact members 55 adapted to be engaged and disengaged by the switch blade, said contact members each having a terminal portion extending to the exterior of the switch at the line of division between the cap and the base and lying in a recess in the base, said terminal portion of the contact member having a noncircular plug fitting a noncircular socket in the base outside of the area there- 60 covered by the cap.

3. A snap switch comprising an insulating 65 body; switch mechanism including a switch blade mounted in said body for oscillation; a contact member adapted to be engaged and disengaged by the switch blade, said contact member having a terminal portion and a switch-blade engaging 70 portion substantially spaced therefrom; and means on the insulating body engaging the switch-blade engaging portions of the contact members adjacent the point of contact thereon 75 by the blade to positively hold said portions

against lateral movement relative to the body.

4. A snap switch comprising an insulating body; switch mechanism including a switch blade mounted in said body for oscillation; a contact member adapted to be engaged and disengaged by the switch blade, said contact member having a terminal portion and a switch-blade engaging portion substantially spaced therefrom; and lugs on the insulating body engaging the switch-blade engaging portion of the contact member adjacent the point of contact thereon by the blade to positively hold said portion against lateral movement relative to the body.

5. A snap switch comprising an insulating body; switch mechanism including a switch blade mounted for oscillation in a narrow chamber in said body; a contact member adapted to be engaged and disengaged by the switch blade, said contact member having a terminal portion and also having a switch-blade engaging portion substantially spaced from the terminal portion and located in said narrow chamber; and means on the insulating body in said narrow chamber engaging the switch-blade engaging portion of the contact member adjacent the point of contact thereon to positively hold said portion against lateral movement relative to the body.

6. A snap switch comprising an insulating body; switch mechanism including a switch blade mounted for oscillation in said body; a contact member removably mounted in a socket on the body and comprising a switch-blade engaging portion; and means on the insulating body engaging the switch-blade engaging portion of the contact member adjacent the point of contact thereon to positively hold said portion against lateral movement relative to the body.

7. A snap switch comprising an insulating body; switch mechanism mounted on said body, said switch mechanism including a switch blade mounted for oscillation and for floating movement; a contact member adapted to be engaged and disengaged by the switch blade and including a rigid switch-blade engaging portion; and means on the insulating body engaging the switch-blade engaging portion of the contact member adjacent the point of contact therewith to positively hold said portion against lateral movement relative to the body for engagement by the floating switch blade.

8. A snap switch comprising an insulating two part body; switch mechanism mounted on said body, said switch mechanism including a switch blade mounted for oscillation and for floating movement; a contact member loosely mounted on one of the body parts and comprising a switch-blade engaging portion; and means on the insulating body engaging the switch-blade engaging portion of the contact member to hold said portion against lateral movement relative to the body for engagement by the floating switch blade.

9. A snap switch comprising an insulating body; switch mechanism including a switch blade

mounted for oscillation in a narrow chamber in said body, said switch mechanism including a switch blade mounted for oscillation and for floating movement; a contact member adapted to be engaged and disengaged by the switch blade, said contact member having a switch-blade engaging portion located in said narrow chamber; and integral means on the insulating body in said narrow chamber engaging the switch blade engaging portion of the contact member to positively hold said portion against lateral movement relative to the body for engagement by the floating switch blade.

10. A snap switch comprising an insulating two part body; switch mechanism including a switch blade mounted for oscillation in a narrow chamber in said body, said switch mechanism including a switch blade mounted for oscillation and for floating movement; a contact member loosely mounted on one of the body parts adapted to be engaged and disengaged by the switch blade, said contact member having a switch-blade engaging portion located in said narrow chamber; and means on the insulating body in said narrow chamber engaging the switch-blade engaging portion of the contact member to hold said portion against lateral movement relative to the body for engagement by the floating switch blade.

11. A snap switch comprising a base; a cap for the base; switch mechanism interposed between and enclosed by the cap and the base and including an oscillating switch blade; contact members loosely mounted on the base having switch-blade engaging portions, some of which are located in the cap and some of which are located in the base; and means on the cap and means on the base for engaging the switch-blade engaging portion of the respective contact members to hold said portion against lateral movement relative to the body.

12. A switch having a base and a cap, the base having a plurality of means adapted to removably hold in operative position thereon a plurality of contact members for removal and replacement without the use of tools, and the cap having means to lock the contact members on the base against removal when the cap is secured to the base and the contact members having wire clamping terminal portions lying outside said cap.

13. A snap switch having an insulating body and a cover; a plurality of sockets in the body; contact units, each including a terminal post having a section thereof removably fitting into one of said sockets and having a portion thereof exposed outside of the body and cover for the connection of feed wires and each terminal post having secured thereto a contact piece located within the body; and means on the cover to lock the contact units on the body against removal and to release the contact units for removal when the cover is removed from the body.

ARTHUR C. GAYNOR.
